NIGHT LIGHT

Robert Goldman and Lillian Goldman, Louisville, Ky., assignors to Lili, Inc., Salem, Ind., a corporation of Indiana

Filed Aug. 18, 1961, Ser. No. 66,413

Term of patent 7 years

(Cl. D48—20)

Fig. 1.

Fig. 2.

Fig. 3.

Fig. 4.

FIG. 1 is a front elevational view of our night light, showing our new design.

FIG. 2 is a rear elevational view thereof.

FIG. 3 is a top plan view thereof with the base omitted for convenience of illustration.

FIG. 4 is a sectional view taken on the lines 4—4 of FIG. 1 in the direction of the arrows.

We claim:

The ornamental design for a night light, as shown and described.
